CLOSURE CAP

Lawrence M. Curtiss, Mountainside, N.J., assignor to The Thomas & Betts Co., Incorporated, Elizabeth, N.J., a corporation of New Jersey

Filed Nov. 26, 1963, Ser. No. 77,574

Term of patent 14 years

(Cl. D58—26)

Fig. 1

Fig. 2

Fig. 3

Fig. 4

This application is a continuation in part of my application, Serial No. D. 77,005, filed October 15, 1963, now abandoned.

I claim:

The ornamental design for a closure cap, as shown and described.
